UNITED STATES PATENT OFFICE

THOMAS A. JOHNSTON, OF FREMONT, NEBRASKA.

CAB OR CAR AWNING.

SPECIFICATION forming part of Letters Patent No. 537,642, dated April 16, 1895.

Application filed June 19, 1893. Renewed October 11, 1894. Serial No. 525,637. (No model.)

To all whom it may concern:

Be it known that I, THOMAS A. JOHNSTON, of Fremont, in the county of Dodge and State of Nebraska, have invented certain useful Improvements in Cab or Car Awnings; and I do hereby declare that the following is a full, clear, and exact description of the invention, such as will enable others skilled in the art to which it appertains to make and use the same, reference being had to the accompanying drawings, which form a part of this specification.

This invention has relation to a new and novel collapsible awning, adapted to be used on locomotive cabs and railway cars and coaches.

In the accompanying drawings, Figure 1 shows a bottom view of my improved awning, as extended and open. Fig. 2 shows a front view of Fig. 1, showing a portion of the locomotive cab. Fig. 3 is an end view of Fig. 2. Fig. 4 is a broken section of the spring actuated curtain roll; while Fig. 5 shows my improved curtain in a closed condition.

25 A represents the cab of a locomotive as usually constructed to which my curtain is to be attached.

In securing my device to a locomotive or car I prefer attaching the same to a panel B, of any suitable length and material. To this panel is secured my improved curtain.

25 2 represents the end caps of the roll 5, giving support to the curtain 6. This roll is an ordinary spring actuated curtain roll, as is usually employed, and the curtain 6, may be of any suitable material, such as oil cloth or canvas. To the free end I secure a rod 7, as shown.

30 3 and 4, 4, represent the bearing ears, by means of which the rods comprising my improved frame are held.

Secured to the rod 7, are two depending clamps 8, the lower portions 9, of which are recurved so as to give support to a depending panel 30. The clamps 8, are provided upon the rear with an ear 11, adapted to engage the nut 12, and this ear 11, forms the clamp in conjunction with the bar 8. This clamp is adjustable upon the frame and may be secured at any suitable point.

35 Secured to the ears 13, are the rods 14, 14, and 15, 15, which are articulated and are

adapted to fold upon one another but which when opened will be held in a straight line, as shown in Fig. 1, in the manner of a hinge; 55 these rods 14 and 15, really actuating similar to a hinge.

17 represents a transverse bar, which is secured to the rods 14. By means of the pins 16, to the ears 4, 4, are secured the slotted trigger bars 20 and 26, which slide upon the bars 4 by means of pins 21 and 27. The trigger bar 20 is connected to the bars 17 by means of the connecting rod 18, while the trigger bar 26 is connected to the bar 17 by 60 means of the rod 28, working within one end of the pivoted lever arm 22, and then being connected to the rod 17 by means of the intermediate rod 19.

The ear 24, is extended by means of the bar 70 25, which forms part of the ear 4, as is shown in Fig. 2, the bar 25 and 25' being in one piece and giving support at the end to the slotted trigger bar 26, by means of the bearing ear 24.

To further secure the awning and prevent 75 the wind from carrying it upward or sidewise, I provide the chains 33, 33, and 34, which are secured to the sides of the cab or car. The chain 34 is preferably hooked over the rod 7, and below is secured to the ring, 35.

The panel 30, which depends from the awning, is adapted to prevent the sun from entering through and is secured to the adjustable clamps 8, by means of an ordinary thumb screw 40, and the transverse bars 41, so that 80 this panel can be readily removed if desired.

The operation of my device would be as follows: If a car or cab equipped with my improved awning should enter a bridge which would not permit the extension of the awning, the trigger bars 20 or 26 would come in collision with the bridge post or any other obstruction which the coach might encounter. In entering a tunnel, for instance, (which is usually very narrow and would not permit 90 the entering of the car with a permanent awning, as the distance from awning to awning would be greater than that usually allowed,) the trigger bar 26, would be encountered. It would be upset, and in being carried forward 100 the lower end of this trigger bar 26, would drag the rod 28, outward, and this rod would carry the upper end 23, of the lever 22, in the same direction, so that the lower end would

be forced in a direction opposite and so carry the rod 19, outward, and this rod 19, would upset the hinged articulated rods 14 and 15, and so permit the spring actuated roll 5, to 5 instantly coil up the curtain and so carry it out of the path of the obstruction before the curtain could be injured. In this position the curtain would be nicely folded against the car, as is shown in Fig. 5. If the car 10 should go in the opposite direction the trigger bar 20, would be encountered, when the device would be more promptly closed, as there are no intermediate rods or levers necessary to bring about this effect.

15 The device is exceedingly simple and is adapted to be used in connection with any ordinary car, coach or vehicle; and,

Having thus described my said invention, what I claim as new, and desire to secure by 20 United States Letters Patent, is—

1. In a collapsible awning, the combination with a suitable support, of a spring actuated roll, a curtain secured to said roll, articulated rods suitably supported and secured at their 25 outer ends to the free end of said curtain, and two slotted trigger bars secured to said articulated bars, to upset and close said bars and curtain, all substantially as and for the purpose set forth.
- 30 2. The combination in a collapsible awning of a suitable supporting panel, of a spring actuated roll, a curtain secured to said roll, provided at its free end with suitable clamps, articulated rods secured to said clamps and

working within suitable ears, a transverse 35 bar connecting said articulated rods, and two slotted trigger bars secured to said articulated rods by means of suitable connecting bars, one of said trigger bars being provided with an intermediate lever and rod so as to upset 40 said curtain when said trigger bars are carried out of position, all substantially as and for the purpose set forth.

3. In a collapsible awning, the combination with a suitable supporting panel, of the supports 2, 2, the supporting ears 3, 3, and 4, 4, the spring actuated roll 5, provided with the curtain 6, provided at its free end with the rod 7, clamps 8, provided at their lower ends with recurved portions adapted to removably 50 hold a panel, the articulated hinged bars 14 and 15, secured to the clamps 8, and the ears 3, and the two slotted trigger bars 20 and 26, the slotted bar 20 being connected to the transverse bar 17 by means of the rod 18, 55 while the trigger bar 26, is connected to said bar 17 by means of the rod 28, lever 22, and rod 19, said slotted trigger bars being adapted when carried out of position to upset said articulated hinged bars 14 and 15, all substantially as and for the purpose set forth.

In testimony whereof I affix my signature in presence of two witnesses.

THOMAS A. JOHNSTON.
